[57] **CLAIM**

The ornamental design for an desk mountable air distribution unit to be attached to a hose, as shown and described.

DESCRIPTION

FIG. 1 is a front elevation of the desk mountable air distribution unit to be attached to a hose;

FIG. 2 is a rear elevation of the desk mountable air distribution unit to be attached to a hose;

FIG. 3 is a side elevation of the desk mountable air distribution unit to be attached to a hose;

FIG. 4 is an opposite side elevation of the desk mountable air distribution unit to be attached to a hose;

FIG. 5 is a plan view of the desk mountable air distribution unit to be attached to a hose;

FIG. 6 is an underneath view of the desk mountable air distribution unit to be attached to a hose; and,

FIG. 7 is a front perspective view of a modified embodiment of the desk mountable air distribution unit to be attached to a hose.

The sole difference between the first and second embodiments, is the length to width ratio of the air distribution unit.

FIG. 1

FIG. 2

FIG. 3

FIG. 4

FIG. 5

FIG. 6

FIG. 7
